CLOSURE

Oliver D. Kingsland, Rochester, N. Y.

Application April 18, 1940, Serial No. 330,417

5 Claims.

(Cl. 268—30)

This invention relates to a vertical sliding gate or door comprising a plurality of slidably mounted gate or door sections and means for raising and lowering said sections for positioning them in a raised, nested position, for opening the door or gate, and in a lowered, extended position for closing the door or gate.

More particularly, it is an aim of this invention to provide a door or gate including a plurality of door or gate sections slidably mounted in a perpendicular frame including means for simultaneously opening and closing the gate or door sections.

Still another aim of the invention is to provide a safety device carried by the lowermost door or gate section and adapted to be actuated by the lower edge of said section contacting an obstruction for actuating latch means for latching the sections against movement relatively to their frame.

Still another object of the invention is to provide means, including a reversible electric motor for driving the shafts to which are connected flexible supporting members for raising and lowering the gate or door sections, and a switch mounted in the circuit of the motor to open or break the circuit to the motor should the weight of one or more of the door or gate sections be removed therefrom.

Other objects and advantages of the invention will hereinafter become more fully apparent from the following description of the drawings, which illustrate a preferred embodiment thereof, and wherein:

Figure 1 is a front elevational view, partly in section, of the sliding door or gate.

Figure 2 is a vertical sectional view taken substantially along the plane of the line 2—2 of Figure 1.

Figure 3 is an enlarged fragmentary vertical sectional view of a portion of one side of the gate or door substantially at a right angle to the plane of Figure 2, showing the latch means for holding the gate or door sections in a secured position relatively to the frame.

Figure 4 is a diagrammatic view showing the circuit for controlling the electric motor.

Figure 5 is a horizontal sectional view, on an enlarged scale, taken substantially along the plane of the line 5—5 of Figure 1.

Figure 6 is a vertical sectional view taken substantially along the plane of the line 6—6 of Figure 5.

Figure 7 is a top plan view of the door or gate, and

Figure 8 is a vertical sectional view taken substantially along the plane of the line 8—8 of Figure 6.

Referring more particularly to the drawings, 5 wherein like reference characters designate like or corresponding parts throughout the different views, 10 designates generally the door or gate and includes generally an upright arch shaped frame 11 and a door or gate 12 comprising three 10 door or gate sections or panels 13, 14 and 15.

The frame 11 includes the upright, spaced hollow pillars 16 and a horizontal member 17 which is supported on the upper ends of the pillars 16 and which includes the hollow end portions or 15 housings 17', which rest on the upper ends of the pillars 16. The adjacent sides of the pillars 16 are provided with grooves 18 in which are slidably mounted the sections or panels 13, 14 and 15, one of said panels or sections being slidably 20 mounted in each of the grooves 18, as best seen in Figure 2. A shaft 19 is journaled in each of the portions 17' and supports three sprocket wheels 20, 21 and 22, which are keyed to the shaft and disposed within the portion 17'. As 25 best seen in Figure 5, the sprocket wheels 21 are of greater diameter than the sprocket wheels 20 and the sprocket wheels 22 are of greater diameter than the sprocket wheels 21.

Chains 23 are trained over the sprockets 20 30 and are connected at their corresponding ends to the panel or section 13. Chains 24 are similarly mounted relatively to the sprockets 21 and are connected to the panel 14 and chains 25 are similarly trained over the sprockets 22 and connected to panel 15. The chains 23, 24 and 25 35 are disposed in the grooves 18 and extend into the end portions 17' through openings 26 in the bottoms thereof. A shaft 27 is mounted in each of portions 17', said shafts being disposed between

40 a series of the openings 26 and a shaft 19 to mount a plurality of idler sprocket wheels 28 which are rotatably mounted on the shafts 27 and over which the chains 23, 24 and 25 are trained to position the chains to extend perpendicularly of 45 the pillars 16 to prevent them from binding in the grooves 18 and in the openings 26.

The end portions 17' are provided with openings 29 which communicate with the pillars 16 and through which the opposite ends of the said 50 chains 23, 24 and 25 extend. The chains 23 and 25, in each of said sets, are joined or formed integral at their opposite ends and said joined or integral ends are trained over pulleys 30, each of which is journaled in a hanger 31 which supports a sash weight 32 and which is provided with a

hook or eyelet 33 at its top to which is connected the free end of a chain 24. It will thus be seen that each set of chains 23, 24 and 25 is connected to a sash weight 32, one of which is disposed in each of the pillars 16. The two sash weights combine to counter-balance the weight of the panels or sections 13, 14 and 15.

The reversible electric motor 34 is mounted in the member 17, intermediate of its ends, and is provided with a driven shaft 35 to which is keyed a worm 36. A shaft 37, formed of three sections which are connected by universal joints 38, includes an intermediate section which is journaled, adjacent its ends in the bearings 39 which are secured to the member 17. The said intermediate section is provided with a worm gear 40 which meshes with the worm 36 for driving the shaft 37. Referring particularly to Figures 5 and 7, the remote ends of the end sections of the shaft 37 are journaled in the yoke shaped bearings 41 which are provided with intermediate bearing portions 42 in which are journaled the forward ends of the shafts 19 which shafts support the bearings 41 and thereby support the end sections of the shaft 37. The yoke shaped bearings 41 are held in place on the shafts 19 by means of pin and groove connections 43. Each of the end sections of the shaft 37 is provided with a worm 44 to mesh with a worm gear 45 keyed to the shaft 19. One of the worms 44 is provided with a right hand thread, while the other worm 44 is provided with a left hand thread so that when the shaft 37 is driven by the motor 34 it will drive the shafts 19 simultaneously in opposite directions for simultaneously raising or lowering the ends of the chains 23, 24 and 25 which are connected to the panels or sections, 13, 14 and 15.

The shafts 19 are mounted or extend through elongated vertical slots or openings 46 in the front and rear walls of the housings 17' to provide for a vertical movement of the shafts 19, for a purpose which will hereinafter become apparent. A cylinder 47 is mounted on each of the front and rear walls of the two housings 17', as best seen in Figure 6. Each of the cylinders 47 is open at its upper end and is provided with an interiorly disposed collar 48 fixed therein, adjacent its lower end and forming a bearing in which is slidably mounted a plunger rod 49 which is provided at its upper end with a bearing head 50 for journaling an end of one of the shafts 19. An expansion coil spring 51 is disposed in each of the cylinders 47 with one end thereof bearing against its collar 48 and the opposite end thereof bearing against the bearing head 50 so that the springs 51 of the four cylinders 47 combine to urge the two shafts 19 upwardly against the weight of sections 13, 14 and 15 and the sash weights 32, which are sufficient to hold the springs 51 compressed and the shafts 19 in a lowered position, as seen in Figure 3.

A pair of contacts 52 are mounted in the lower end of one of the cylinders 47, as best seen in Figures 6 and 8, and are insulated from one another by means of the insulation 53. The plunger 49 of this cylinder 47 is provided at its lower end with a metallic bar 54 which normally rests on the contacts 52 to form a connection therebetween. The parts 52, 53 and 54 combine to form a switch, designated generally 55 which is interposed in an electric circuit of the motor 34, as seen in the diagrammatic view, Figure 4. In this figure, a source of electric current such as a battery indicated at 56 having a conductor 57 extending therefrom to one of the terminals of

the motor 34, said conductor being provided with a switch 58. A conductor 59 extends from the other terminal of the motor 34 to one of the contacts 52 while a conductor 60 extends from the other contact 52 to the opposite side of the battery 56 so that when the switch 58 and the switch 55 are closed the motor 34 will be energized to revolve the shaft 35. As any form of reversible electric motor may be used in operating the panels or closure sections, the switch means for reversing the direction of movement of the motor 34 has not been disclosed as any such means could obviously be employed. A conductor 61 provided with a switch 62 connects the conductors 59 and 60 around the switch 55 so that when the switch 62 is closed its circuit will be completed to the motor 34 with the switch 55 in an open position, through the switch 58, conductors 57, 59 and 61, switch 62 and conductor 60.

Assuming the parts to be in position, as seen in Figure 1, the switch 58 and 62 in an open position and the switch 55 held in a closed position by the weight of the panels 13, 14 and 15 and the sash weights 32, the switch 58 is closed to complete the circuit to the motor 34 for driving the shaft 19, at the right hand side of Figure 1, in a clockwise direction and the other shaft 19 in a counter-clockwise direction. The movement of the shafts 19 will revolve the sprockets 20, 21 and 22 carried thereby to pull upwardly on the ends of the chains 23, 24 and 25 which are attached to the panels or closure sections to cause said sections to be raised, at different speeds, as heretofore explained, due to the difference of the sizes of the sprockets, so that the section 14 will be moving faster than the section 13 and the section 15 will be moving faster than section 14 to cause the three sections to reach the raised, open position simultaneously with said sections in a nested position relatively to each other. The sash weights 32 counter-balance the weight of the closure sections. When the sash weights 32 move downwardly the ends of the chains 25, which are joined with the ends of the chains 23, will be payed out relatively to the hangers 31 thereby drawing the corresponding ends of the chains 23 inwardly of the hangers 31 to compensate for the differences in speeds at which chains 23 and 25 are moving. The motor is reversed to rotate the shaft 35 in the opposite direction, the two shafts 19 will be revolved in opposite directions, or more specifically, the left hand shaft 19 will be turning clockwise and the right hand shaft 19 will be turning counter-clockwise to raise the weights 32 to thereby allow the panels or sections 13, 14 and 15 to slide downwardly at the same variable speed so that the panels will simultaneously reach their extended, closed position, as seen in Figure 1. When the sash weights 32 are drawn upwardly the joined ends of chains 23 and 25 will move relatively to the hangers 31 conversely to the manner heretofore described, or in other words, chains 23 will be payed out relatively to the hangers 31 while the chains 25 will be drawn inwardly thereof to compensate for the different speeds at which 23 and 25 are moving. It will thus be seen that when the switch 55 is in a normally closed position, the switch 58 is normally employed to energize or deenergize the motor 34 for operating the gate or door sections 13, 14 and 15.

The lower-most panel 15 is provided with a bottom rail 63 comprising the section 64 which is hollow and to which is connected section 65, which is disposed therebeneath, and which is

adapted to telescope into the section 64, as best seen in Figures 2 and 3. The section 64 is provided with inturned lower edges 66 to engage under the outturned edges 67 of the section 65, as best seen in Figure 2, to hold said sections in connected relationship. A depending hanger 68 is secured in section 64, adjacent each end thereof, and extends part way into section 65. A lever 69 is pivotally connected to the lower end of each of the hangers 68 and includes the arms 70 and 71 which are disposed of obtuse angles to each other and which are provided at their free ends with rollers 72. The chains 23, 24 and 25 are connected to the sides of the panels 13, 14 and 15 by means of brackets 73, one of which is seen in Figure 3. The brackets 73, carried by the panel 15, are also provided with pins 74 to which are pivotally connected the upper ends of a pair of pawls 75 which are provided with flat relatively wide heads 76, at their lower ends, which extend through slots 77 in the side edges of the panel 15 and into the lower rail 63, as best seen in Figure 3. The pawl 75, as seen in Figure 3, is shown in its normal, retracted position with the inner edge of its head portion 76 engaging against the roller 72 of one of the arms 71 to hold the lever 69, of which said arm 71 forms a part, in a position so that arm 70 will extend downwardly and be disposed with its roller 72 engaging the base portion of telescoping section 65. A perpendicularly disposed rack bar 78 is secured to each of the pillars 16 and extends into the opening of the frame 11, as best seen in Figure 1 (this latch structure, as heretofore described and as best illustrated in Figure 3, is claimed in my co-pending application entitled Safety latch for sliding closures, filed November 20, 1940, and bearing Serial No. 366,493).

Assuming that the panels 13, 14 and 15 are moving downwardly or toward a closed, extended position and their path is obstructed, as by means of a person standing in the frame opening, section 65 of the bottom rail 63 will strike the obstruction and be retracted thereby into the section 64 to thereby swing the arms 70 of the levers 69 upwardly to rock the arms 71 outwardly and cause the pawls 75 to be swung outwardly so that the portions 79 of their heads 76 will engage corresponding notches of the rack bars 78 to latch the panel 15 relatively to the frame 11. This will release a portion of the weight supported by the shafts 19 to permit the springs 51 to expand to raise the shafts 19 and to open the switch 55 to break the circuit to the motor 34 to thereby prevent further movement of the other panels 13 and 14. In order to release the panels, the closure must be raised to an open position which is done by reversing the motor and closing the switch 62 to thereby complete the circuit to the motor 34 and start the panels moving upwardly and to cause the switch 55 to resume its closed position to again complete the original circuit, at which time switch 62 can be again opened and the original circuit controlled by means of the switch 58. Should one or more of the chains 23, 24 and 25 break thereby releasing a portion of the lead from the shafts 19 the springs 51 will expand to break the circuit through the switch 55 in the same manner as heretofore described.

Various modifications and changes in the construction and arrangement of the parts forming the sliding gate or door are contemplated and may obviously be resorted to as the drawings

and description thereof are only intended as an illustration and description of a preferred form of the invention.

I claim as my invention:

- 5 1. A gate comprising an upright frame, a plurality of panels slidably mounted in said frame for closing the frame opening when disposed in an extended position relatively to each other, a shaft journaled in the upper portion of said frame, a plurality of sprocket wheels, of different diameters, keyed to the shaft, chains connected to said panels, at corresponding ends thereof, and trained over said sprocket wheels, a weight connected to the opposite ends of said chains for counterbalancing the weight of said panels, said shaft being rotatable for simultaneously raising and lowering the panels, at different speeds, whereby the panels will simultaneously reach an extended position for closing the frame opening or a nested position at the top of the frame for exposing the frame opening, an upright rack bar formed in one side of said frame, said lower-most panel being provided with a bottom rail formed of telescoping sections, a rocker arm pivotally mounted in said bottom rail, and latch means connected to said bottom panel and engaging an end of said rocker arm, and said rocker arm being actuated when said telescoping sections are retracted for moving the 20 latch means into engagement with the rack bar for latching the bottom panel to the frame and for cooperating with the chains and sprocket wheels for holding the other panels from moving downwardly in the frame.
- 25 2. A closure comprising an upright arch, forming a closure frame, three closure sections slidably mounted in said frame, a shaft journaled in the upper portion of the arch, three sprocket wheels of different diameters keyed to said shaft, chains connected to said closure sections and trained over said sprocket wheels for raising and lowering the sections when the shaft is revolved whereby the closure sections will be moved simultaneously at different speeds for either simultaneously positioning the sections in an extended position relatively to each other, or in a nested position, said chains being of different lengths, the longer chain being trained over the largest sprocket and connected to the lower-most closure section, the next longest chain being connected to the intermediate closure section and trained over the intermediate sized sprocket wheel, and the shortest chain being connected to the upper-most closure section and trained over the smallest sprocket wheel, and a weight having a supporting hanger provided with a pulley, the longest and shortest chains being joined at their opposite ends and trained over said pulley, and the intermediate chain being connected to said hanger, said weight forming a counter-balance weight for the three closure sections.
- 30 3. A closure comprising a frame, a plurality of closure sections slidably mounted therein, a shaft journaled in the upper portion of the frame, sprocket wheels of different diameters keyed to said shaft, chains connected to said closure sections and trained over the sprocket wheels for raising and lowering the sections when the shaft is revolved whereby the closure sections will be moved at different speeds for either simultaneously positioning the sections in an extended or in a nested position, relatively to each other, an electric reversible motor connected to said shaft for rotating it in either direction for rais-

ing and lowering said closure sections, a switch connected to the electric circuit of said motor including a plunger having a bearing portion forming a journal for said shaft, said switch being normally held in a closed position by the weight of said closure sections which are supported by said shaft, and spring means co-acting against the weight of the closure sections for raising the plunger to open the circuit when one of the chains is broken to thereby reduce the weight on the shaft.

4. A vertically sliding closure comprising a perpendicular, arch shaped frame, a plurality of sections slidably mounted in said frame and combining to form a sliding closure, driven shafts journaled in the upper portion of said frame, flexible supporting means connected to said closure sections, means keyed to said shafts and over which said flexible supporting means are trained for raising lowering the sections when said shafts are revolved, a reversible, electric motor connecting to and driving said shafts for raising and lowering the closure sections, said sections being movable simultaneously at variable speeds to cause the sections to reach a closed, extended position or an open, nested position simultaneously, bearings for journaling said shafts, spring means for urging the said bearings upwardly, and a switch associated with

5 one of said bearings, the weight of said closure sections normally holding said shafts and bearings in a lowered position for closing said switch, said switch being interposed in the electric circuit of said electric motor for breaking the circuit thereto when the weight of closure sections on the shafts is released or reduced.

5. A closure comprising an upright frame, a plurality of closure sections slidably mounted therein, a shaft journaled in the frame, a plurality of sprocket wheels of different diameters keyed to the shaft, a reversible electric motor for rotating the shaft in either direction, chains connected to the closure sections and trained 15 over the sprocket wheels, said chains being arranged on the sprocket wheels to cause the closure sections to move at variable speeds so as to simultaneously reach open and closed positions, latch means associated with one of the closure sections and frame to latch said section to the frame when it encounters an obstruction in the frame opening and to combine with the sprocket wheels and chains to stop the movement of the other closure section, and a weight 20 actuated switch associated with the shaft and actuated by the first mentioned closure section being latched to the frame for breaking the circuit to the electric motor.

OLIVER D. KINGSLAND.
